FREDRIC E. DOUGLAS, OF HOPEDALE, MASSACHUSETTS, ASSIGNOR TO DRAPER CORPORATION, OF HOPEDALE, MASSACHUSETTS, A CORPORATION OF MAINE

INTERMITTENTLY OPERATING THREAD CUTTING MECHANISM

Application filed December 29, 1932. Serial No. 649,423.

The present invention relates to thread cutting temples for looms, and has more particular reference to means for rendering the thread cutting mechanism thereof intermittent in operation.

In automatic filling replenishing looms, of the type wherein a bobbin or shuttle containing a fresh supply of filling is automatically inserted when needed, the outgoing filling end and the incoming end are trimmed off adjacent the selvage of the cloth within a few picks after the filling replenishing operation, the cutting or trimming of the filling ends being accomplished by a thread cutting mechanism embodied in the temple. Ordinarily such thread cutting mechanisms are operated by or through the lay, and operate continuously regardless of whether or not a filling thread is adjacent the temple in position to be cut, this construction entailing hundreds of idle operations of the cutting mechanism to each useful cutting stroke.

It has been heretofore proposed to provide the thread cutting temples with a timing mechanism for rendering the cutting mechanism inoperative after a relatively small number of picks, and a resetting means, operated upon call for filling replenishment, for resetting the timer and restoring the cutting mechanism to operation. In general, the timing device of such prior constructions has included a ratchet wheel together with more or less complex mechanism for operating the same, although attempts have been made to employ a frictionally retarded gravity operated slide, as a timer. The ratchet-wheel devices are too complicated to be of practical value, and the frictionally retarded slides have proven unreliable, with the result that, insofar as I am aware, no intermittently operating thread cutting temple of the types mentioned is in commercial use.

I propose to provide a thread cutting temple having a timing device for rendering the thread cutting mechanism inoperative, which timing device shall be simple in construction and reliable in operation.

To this end the invention comprehends the utilization of a gravity operated rack member, positively controlled in its movements

and capable of engaging, and rendering inoperative, the movable member of the thread cutting mechanism.

Two preferred embodiments of the invention are illustrated on the accompanying drawings, in which:

Figure 1 is a side elevation of the thread cutting temple and associated mechanism, contiguous parts of the loom being shown in section or in dotted outline;

Figure 2 is a fragmentary view, to a larger scale, of the temple shown in Figure 1, the same being dissociated from the loom;

Figure 3 is a view similar to Figure 2, but showing the thread cutting mechanism locked out of operation;

Figure 4 is a vertical sectional view taken substantially on line 4-4 of Figure 3;

Figure 5 is a view, in elevation, of a temple embodying a modified form of my invention;

Figure 6 is a view in cross-section, taken substantially on line 6-6 of Figure 5.

The temple 1, to which my invention has been applied, is reciprocably mounted in a housing 2 supported on the breast beam 3 in any suitable usual manner, not herein disclosed. The temple shown is of right-hand pattern for holding the cloth selvage on the right side of the loom. The temple head, indicated generally at 4, Figs. 1 and 5, is comprised of a cap 5, and pod 6 (see Figure 4) housing a temple roll (not shown), and also includes a depending heel 7 adapted to be struck by the lay 8 on each reciprocation of the latter. All of the foregoing construction is well known in the art and, therefore, need not be further illustrated or described.

Referring first to Figs. 1-4 inclusive, the thread cutting mechanism proper, illustrated but fragmentarily, includes a movable cutter member 9 cooperating with a stationary ledger blade, not shown. The cutter member 9 is provided, at the forward end of the blade portion thereof, with a downwardly extending heel 10 positioned to be struck by the lay on each forward beat of the latter. The cutter member is normally urged rearwardly by means of a suitable spring 11. This thread cutting mechanism is well known

in the art and is not of my invention. Obviously, other types or forms of cutting mechanism may be substituted for that shown.

As above intimated, I have provided a gravity operated rack, and means for positively restricting, or controlling, the downward movement of the same, for rendering the thread cutting mechanism inoperative. The rack, 12, is comprised simply of a flat bar having a pin or roller 13 at its upper end, and being provided front and rear with a series of teeth 14, 15. A vertically extending guide for the toothed rack member 12 is associated with the temple head, preferably by being fastened to the right-hand end thereof.

The guide 16, herein disclosed, consists of a body portion secured to the temple head, as by a screw 17, and vertically apertured to receive the rack member 12, the latter being slidable rectilinearly, i. e. vertically, in the guide. An upwardly projecting extension 17 may be formed on the guide 16, to provide additional support for the rack member.

The rack member is movable between an upper position, shown in Figure 1, and a lower position, shown in Figures 3 and 4. When in its lower position, it is adapted to render the thread cutting mechanism inoperative. To this end, it may be provided at its lower end with means for engaging the movable cutter member and holding the latter out of operation. As herein constructed, the lower front corner 18 of the rack member serves as the aforesaid means, this corner engaging the lug 19 formed on the heel 10 of the movable cutter member 9, as shown more particularly in Figures 3 and 4. It is noted at this time that the rear face of lug 19 is inclined downwardly and slightly rearwardly when the movable cutter member occupies the position shown in Figures 3 and 4, whereby, any slight movement of the member 9, occasioned by its not being held so that heel 10 is entirely forward of the temple heel 7, will result in the rack dropping down a little farther and thus holding the member 9 in its extreme forward position.

It has been stated that the rack 12 is operated by gravity. Obviously, gravity need not be the only force involved. Also, downward movement of the rack is positively controlled, or restricted, by means herein constituted by a single, double-toothed pawl positioned parallel to the plane of movement of the movable cutter member and operated directly thereby. The pawl shown is comprised of a bar 20 pivoted on screw 21 in the guide 16, spring steel wires 22, 23 fixed in the bar 20, and the double-toothed member 24 carried by the wires and operating through a slot formed in the guide 16.

The wires, extend, at their lower ends, on opposite sides of the lug 19, with a proper amount of lost motion, whereby reciprocation

of the cutter member serves to oscillate the pawl. The teeth 14 of the rack are staggered with relation to teeth 15, i. e. each tooth 14 is opposite the space between two teeth 15. Thus, each complete reciprocation of the cutter member will, through the pawl, permit the rack to be lowered a distance equal to the pitch of the teeth. If there are ten teeth on each side of the rack, raising the latter to the position shown in Fig. 1 will result in the cutting mechanism operating ten times before it is rendered inoperative.

Any suitable means, operative upon call for filling replenishment, may be provided for raising the rack. The particular means employed at present consists of an arm 25 fixed on rod 26 and connected with bell-crank lever 27 by means of a link 28. The rod 26 is a usual part of the filling replenishing mechanism, and is oscillated in the direction of the arrow, Figure 1, upon call for such replenishment. The arm 29 of the bell crank lever 26 engages under roller 13 on rack 12 to raise the latter at the desired time.

The thread cutting mechanism illustrated in Figs. 5 and 6 includes the movable cutter member 30, cooperating with a stationary ledger blade and having a downwardly extending heel 31, as in the previously described construction. The cutter member 30 is normally urged rearwardly by a spring 32. The gravity operated rack 33 is substantially circular in cross-section, except that it is flattened, or slabbed, on the front side to provide a plane surface in which is formed a series of teeth 34.

The guide 35 for the rack is, in the present instance, cast integrally with the temple head. This guide extends approximately vertically, although it should be understood that when I say the guide is "vertical" I mean merely that it is approximately so, as a slight deviation from a true plumb line will in no wise affect the operation of the rack, and such deviation may be intentional, or may be merely an incident to the varying of the position in which the temple is mounted on the loom.

Forwardly extending ears 36 are formed integral with the guide, on opposite sides of a slot 37 therein. A double pointed, double acting pawl 38 is pivoted on a pin 39 in the ears 36 and cooperates with the teeth 34 on the rack member. A steel spring 40, fixed to the pawl, extends downwardly and is looped around a pin in a lug 41 formed on the movable cutter member 30. The spring 40 is of sufficient strength that the first portion of the forward, cutting movement of the cutter member 30 will result in the pawl being rotated, clockwise in Fig. 5, to release its lower point from one tooth in the rack and engage its upper point a slight distance beneath another tooth thereof, whereupon the rack slides downwardly, by gravity, until the

last mentioned tooth contacts the upper point of the pawl. Continued forward movement of the movable cutter, after moving the pawl, merely flexes the spring 40. When the cutter returns to its rearward position, the rack 5 will slide down another half-tooth distance, by a similar process.

An inclined face 42 formed on the movable cutter member is engaged by a similarly shaped face on the lower end of the rack 33 when the latter is in its lowermost position, thus locking the movable cutter member out of operation. The rack may be raised, at the time of transfer, by suitable connections to a 15 bell-crank lever 43 which engages a pin 44 in the upper end of the rack.

It is, of course, to be understood that numerous changes may be made in the construction shown, without departing from the spirit 20 of the invention as defined in the appended claims.

I claim:

1. A thread cutting temple for automatic filling replenishing looms comprising, a temple head, thread cutting mechanism positioned therein, a gravity operated rack adapted when in its lower position to render said thread cutting mechanism inoperative, means operative upon call for filling replenishing 30 to raise said rack and thereby restore said thread cutting mechanism to operation, and means including a pawl for controlling the downward movement of the said rack.

2. A thread cutting temple for automatic filling replenishing looms comprising, a temple head, thread cutting mechanism positioned therein, a gravity operated rack adapted when in its lower position to render said thread cutting mechanism inoperative, means 40 operative upon call for filling replenishment to raise said rack and thereby restore said thread cutting mechanism to operation, and means including a pawl oscillated from the said thread cutting mechanism for positively 45 restricting the downward movement of the said rack.

3. A thread cutting temple for automatic filling replenishing looms comprising, a temple head, thread cutting mechanism positioned therein, said thread cutting mechanism including a lay-operated movable cutter member, a gravity operated rack adapted when in its lower position to render said movable member inoperative, means operating upon 50 call for filling replenishment to raise said rack and thereby restore said movable member to operation, and means including a pawl for positively restricting the downward movement of the said rack.

60

4. A thread cutting temple for automatic filling replenishing looms comprising, a temple head, thread cutting mechanism positioned therein, said thread cutting mechanism including a movable cutter member adapted to be reciprocated by the lay, a vertically extending guide associated with said temple head, a toothed rack member mounted in said guide for vertical sliding movements, said rack being provided at its lower end with means for engaging said movable member and holding the latter out of operation, means operative upon call for filling replenishment to raise said rack and thereby restore said movable member to operation, and means including a pawl operated by said movable member for lowering said rack.

5. A thread cutting temple for automatic filling replenishing looms comprising, a temple head, thread cutting mechanism positioned therein, said thread cutting mechanism including a movable cutter member adapted to be reciprocated by the lay, a guide associated with said temple head, a toothed rack member mounted in said guide and movable rectilinearly to and from a position where it directly contacts the said movable member and holds the latter out of operation, means operative upon call for filling replenishment to withdraw the said rack from said position and thereby restore said movable member to operation and means for returning said rack to said position in a predetermined number of picks, the said last-mentioned means including a pawl positioned parallel to the plane of movement of the said cutter member and operated directly thereby.

6. A thread cutting temple for automatic filling replenishing looms comprising, a temple head, thread cutting mechanism positioned therein, said thread cutting mechanism including a movable cutter member adapted to be reciprocated by the lay, a vertically extending guide associated with said temple head, a gravity operated rack member mounted in said guide for vertical sliding movements, said rack being provided at its lower end with means for engaging said movable member and holding the latter out of operation, means operative upon call for filling replenishment to raise said rack and thereby restore said movable member to operation, and means including a pawl for restricting the downward movement of the said rack, said pawl being positioned parallel to the plane of movement of the said cutter member and operated directly thereby.

FREDRIC E. DOUGLAS.
